US00D516382S

(12) **United States Design Patent** (10) Patent No.: **US D516,382 S**
 King et al. (45) Date of Patent: **** Mar. 7, 2006**

(54) **PLATE DESIGN**

(75) Inventors: **Walter W. King**, Quogue, NY (US);
Walter King, III, Wilmington, NC (US)

(73) Assignee: **American Greetings Corporation**, Cleveland, OH (US)

(**) Term: **14 Years**

(21) Appl. No.: **29/186,611**

(22) Filed: **Jul. 18, 2003**

(51) LOC (8) Cl. **07-01**

(52) U.S. Cl. **D7/553.8**

(58) Field of Classification Search **D7/553.8, D7/553.1, 553.6, 554.2, 555.1, 574, 548, D7/360; 220/574, 23.8; 229/106; 211/74; 493/167; D9/431**

See application file for complete search history.

Primary Examiner—Charles A. Rademaker

(74) Attorney, Agent, or Firm—Roetzel & Andress

(57) **CLAIM**

The design for the plate design, as shown and described.

DESCRIPTION

FIG. 1 is a top, front and right side perspective view of the plate design;
 FIG. 2 is a front elevation view of the embodiment of FIG. 1;
 FIG. 3 is a back elevation view of the embodiment of FIG. 1;
 FIG. 4 is a top plan view of the embodiment of FIG. 1;
 FIG. 5 is a bottom plan view of the embodiment of FIG. 1;
 FIG. 6 is a right side view of the embodiment of FIG. 1; and,
 FIG. 7 is a left side view of the embodiment of FIG. 1.

1 Claim, 3 Drawing Sheets
